UNITED STATES PATENT OFFICE.

HERMAN FISCHER, OF NEW YORK, N. Y.

SHOE.

SPECIFICATION forming part of Letters Patent No. 729,314, dated May 26, 1903.

Application filed February 4, 1903. Serial No. 141,797. (No model.)

To all whom it may concern:

Be it known that I, HERMAN FISCHER, a citizen of the United States, residing in New York, borough of Brooklyn, in the State of New York, have invented certain new and useful Improvements in Shoes, of which the following is a specification.

The object of this invention is to provide a practical and durable concealed or disguised elastic closure for a boot or shoe.

The invention relates more particularly to an elastic closure for a low-cut shoe, in which, owing largely to the severe strains at the sides of the upper, it has been found impractical to employ the ordinary elastic goring at these points.

The invention consists in the combination, in a shoe, of a slotted upper, an elastic lacing connecting the sides of said upper, an elastic webbing at the interior of the shoe, and a movable tongue having free side portions extending between said webbing and the upper.

The invention consists, further, of certain other combinations of parts, which will be fully described hereinafter and finally pointed out in the claims.

In the accompanying drawings, Figure 1 represents a perspective view of my improved shoe. Fig. 2 is a top view of a portion of the upper. Fig. 3 is a vertical transverse section on line 3 3, Fig. 1; and Fig. 4 is a vertical longitudinal section on line 4 4, Fig. 2.

Similar letters of reference indicate corresponding parts.

Referring to the drawings, A indicates the upper of the shoe, which is provided with the usual vertical slit a at its front portion for permitting the opening of the upper sufficiently for application of the shoe to the foot of the wearer. The two portions a' a² of the upper at each side of the slit are retained normally drawn together, so as to close the opening, by means of an elastic lacing b or other suitable elastic medium. At the inside 45 of the shoe is arranged opposite the slit a tongue c, of leather or other suitable material, which is attached at its lower portion c' to the upper. At the inner side of the tongue is arranged a layer of elastic webbing d, which 50 is attached at both sides, beyond the side edges of the tongue c, to the portions a' a² of the upper. In the act of applying the shoe

the elastic lacing and webbing yield sufficiently to permit the entrance of the foot. They then serve to close the upper and retain 55 the shoe upon the foot of the wearer. The elastic webbing and upper form together a pocket within which the tongue is retained. For retaining the tongue centrally in position it is connected by a vertical central line of 60 stitches d' with the webbing, which stitches while retaining the tongue do not in any manner interfere with the free and equal expansion and contraction of the webbing at either side of the same. The tongue being 65 attached at its lower portion to the upper instead of being attached at one of its sides to the same maintains its central position and has no lateral movement in either direction when the shoe is applied. It moves with 70 the upper in outward direction, and its free side portions, located between the upper and webbing, prevent injurious abrasion of the latter against the upper and the eyelets of the same. It is obvious that in case a stiff 75 leather is used for the tongue, so that the same does not wrinkle, it may be attached at one of its sides to the upper, and the webbing in this case need not at that side be attached to the upper at a point beyond the tongue, 80 but may be attached at the same point. In order to provide means for conveniently pulling on and off the shoe, the tongue is extended at its upper end beyond the webbing, as indicated in Fig. 4, so that the same may be 85 grasped without grasping the webbing, which would result in a straining of the same. In order to prevent curling over of the upper edge of the webbing when applying the shoe to the foot, the line of stitches d' is extended 90 entirely to the upper edge of the webbing, also as indicated in Fig. 4. For providing additional means of grasping the tongue, which is especially desirable for heavy shoes, a loop e, of tape or other suitable material, is 95 provided, which is secured at its lower portion to the tongue and extends at its upper or loop portion behind the tongue above the webbing. The finger of the wearer may be readily inserted into this loop, and thereby 100 the tongue pulled in outward direction, so as to open the slit a and permit the entrance of the foot into the shoe. The lower ends of this loop are preferably located one between

the webbing and tongue and the other at the inner side of the webbing, so that the latter end provides also an additional means for preventing curling of the upper edge of the 5 webbing. The webbing, tongue, and loop are all preferably secured in position by the same vertical line of stitches d' . To additionally secure the loop, a second central line of stitches d^2 between the loop and webbing 10 are preferably employed, and the loop is also cemented to the webbing. e' indicates an ornamental bow of any suitable material in imitation of a bow of the lacing. This independent bow is stitched or otherwise secured 15 to the lacing at the top of the upper, or it may be stitched through the slit a to the tongue, so as to retain the same and the webbing when attached in raised position against the upper, this construction being preferable 20 when a tongue of light and flexible leather is employed.

Having thus described my invention, I claim as new and desire to secure by Letters Patent—

25 1. In a shoe, the combination of a slitted upper, an elastic lacing connecting the sides of said upper, an elastic webbing at the interior of the shoe, and a movable tongue having free side portions extending between said 30 webbing and the upper, substantially as set forth.

2. In a shoe, the combination of a slitted upper, an elastic lacing connecting the sides of said upper, an elastic webbing at the interior of the shoe, and a tongue movable with 35 said webbing, and having free side portions

extending between the same and the upper, substantially as set forth.

3. In a shoe, the combination of a slitted upper, an elastic lacing connecting the sides 40 of said upper, an elastic webbing at the interior of the shoe, and a movable tongue connected with said webbing and having free side portions extending between the same and the upper, substantially as set forth. 45

4. In a shoe, the combination of a slitted upper, an elastic lacing connecting the sides of said upper, an elastic webbing at the interior of the shoe, a tongue between said webbing and the upper opposite said lacing, and 50 extending upwardly beyond the webbing, and a loop attached to said tongue and extending upwardly behind the same, substantially as set forth.

5. In a low-cut shoe having an upper provided with a vertical slit at the front portion of the same, the combination of an elastic lacing connecting the sides of said upper across said slit, a tongue at the inside of said upper, and an ornamental bow located at the 60 outside of the upper and stitched through said slit to said tongue for retaining the latter in raised position, substantially as set forth.

In testimony that I claim the foregoing as 65 my invention I have signed my name in presence of two subscribing witnesses.

HERMAN FISCHER.
